UNITED STATES PATENT OFFICE.

HENRY W. WINTER, OF METHUEN, MASSACHUSETTS, ASSIGNOR TO UNITED SHOE MACHINERY COMPANY, OF PATERSON, NEW JERSEY, A CORPORATION OF NEW JERSEY.

TOGGLE.

1,140,428.

Specification of Letters Patent. Patented May 25, 1915.

Application filed August 19, 1910. Serial No. 578,004.

To all whom it may concern:

Be it known that I, HENRY W. WINTER, a citizen of the United States, residing at Methuen, in the county of Essex and State of Massachusetts, have invented certain Improvements in Toggles, of which the following description, in connection with the accompanying drawings, is a specification, like reference characters one the drawings 10 indicating like parts in the several figures.

This invention relates to toggle joints and is herein illustrated in connection with a leather rolling machine. Such machines are commonly provided with two rolls one of 15 which is movable transversely of its axis toward and from the other so that the stock may be subjected to pressure during its passage through the machine. The pressure applied is necessarily very great, one of the 20 results of which is that as the stock passes from between the rolls and the rolls assume their normal position certain parts of the machine are subjected to a sudden heavy strain; and this strain has been particularly 25 destructive to the parts of the toggle or toggles through the agency of which the pressure is commonly applied to the rolls. In order to promote brevity, disadvantages which arise in connection with machines of 30 a certain type have been set forth, but it should be understood that similar disadvantages may arise in connection with various other machines in which toggles are made use of.

Accordingly in order to overcome this and other disadvantages the present invention contemplates as one of its principal objects the provision with a toggle of a member for moving the knuckle of said toggle, 40 actuating means for said member, and a stop for engaging the member whereby the parts of the toggle are relieved of strain. In the illustrated embodiment of the invention the toggle which is arranged to raise 45 the bearings of the lower roll of a leather rolling machine is actuated by the movement of a rod which in a given position contacts with a stop so that the force which up to this point was applied to the toggle is 50 thereafter taken by the stop. With this construction the rolls of the machine are nor-

mally held close together. As soon, however, as they are separated and a piece of stock fed between them the force which was normally applied to the stop is transferred 55 to the toggle, the stock thereby being thoroughly pressed; and when the stock passes from between the rolls the stop once more receives the thrust of the rod, and the parts of the toggles are relieved. Or to state the 60 matter differently, the machine is provided with a movable member which is normally held in a given position through the agency 65 of a toggle, and means are provided for automatically applying force to the toggle when the member is moved in opposition to it and for relieving the toggle from said force when the member is returned through the agency of the toggle to normal position. Preferably, as shown in the illustrated embodiment, a yielding member is provided 70 for holding the toggle in its normal position, and the stop is also acted upon by yielding means. With this construction the rebound of the toggle as the stock leaves 75 the rolls is effectively cushioned.

These and other features of the invention including certain details of construction and combinations of parts will be described in connection with the accompanying drawing and pointed out in the claims.

Referring now to the accompanying drawings: Figure 1 is an elevation of a portion of a leather rolling machine in which one form of my invention is embodied; and Fig. 2 is a detail perspective showing the relation of the push rod to the pivot pin and the ends of the levers of the toggle.

The shaft 1 of the lower roll of the leather rolling machine is supported in bearings one 90 of which is shown at 3, said bearings being 95 slidable in the frame 2. Inasmuch as both bearings of the lower roll are supported by mechanisms which are substantially identical, only one of said mechanisms will be described. Pivoted to the frame of the machine at 5 is a lever 7 provided with a seat for a plate 9, the other end of which is received in a seat in the bearing 3. Also mounted upon the pivot 5 is a second lever 100 11, and threaded through said lever is a screw 13, the outer end of which contacts

with the rear portion of the lever 7. This screw is connected by a universal joint (not shown) with the adjusting rod 15 so that rotation of said rod will vary the angular relation of the two levers. The levers 7 and 11 therefore constitute together a bell crank lever the arms of which are adjustable so that the normal position of the lower roll may be varied. Pivoted at 17 to the lower 5 end of the lever 11 is a toggle lever 19, said toggle lever being pivoted by a pin 21 to a second toggle lever 23 which in turn is pivoted to the frame of the machine at 25, the toggle levers being provided with overlapping yokes 27 and 29 through which the pin 21 passes.

In order to move the knuckle of the toggle downwardly to exert pressure upon the piece of stock which is passing between the 10 rolls, a push rod 31 is provided which is pivotally mounted upon the pin 21 and is formed with an extension 33 for a purpose presently to be described. Any suitable 15 means for applying power to the rod 31 may be employed, and in the illustrative machine a spring 35 surrounding said rod bears at one end against a bracket 39 and at the other end against a shoulder 37 on the rod. This bracket is carried by a plate 41 which slides 20 in guideways 43. A hand wheel 45 is fast to a shaft 46 which is rotatably mounted in the bracket 39. This rod carries at its opposite end a beveled gear, not shown, which meshes with a second beveled gear, also not 25 shown, carried by an upright shaft which is rotatable in the bracket 39, but held from longitudinal movement with respect thereto, the lower end of this upright shaft being threaded into the frame of the machine. It 30 will be clear therefore that by rotating the hand wheel 45 the bracket 39 may be raised or lowered and the tension of the spring 35 thereby varied.

In order to limit the downward movement 40 of the knuckle of the toggle, a stop 47 is slidably mounted in a bore in a bracket 49 which depends from the frame of the machine, said stop being yieldably supported by a spring 51. The stop 47 is provided 45 with a stem 52 upon which are threaded nuts 53 by which the normal position of the stop as well as the tension of the spring 51 may be varied. A treadle, not shown, is provided by which the operator may des- 50 press the lower roll when it is desired to feed a piece of stock to the machine.

It will be observed that the extension 33 on the rod 31 contacts with the stop 47 in the normal position of the parts of the machine and that in said position the thrust of the spring is taken by the stop. If now the roll is separated and a piece of stock is fed through the machine, power is at once automatically applied to the toggle by the spring 60 35 and remains so applied until the stock

passes from between the rolls whereupon the extension 33 once more contacts with the stop 47.

Having thus described my invention, what I claim and desire to secure by Letters Patent of the United States is:—

1. The combination with a toggle, a member arranged to move the knuckle of said toggle, actuating means for said member, and a stop for engaging said member whereby the parts of the toggle are relieved of strain.

2. The combination with a toggle of a spring for normally holding said toggle in a given position, and means for relieving the parts of said toggle from the thrust of said spring while the toggle is in said position.

3. The combination with a stop, a rod and yielding means for normally causing said rod to contact with said stop, of a toggle operably connected therewith, the knuckle of which is movable with said rod away from said stop.

4. The combination with a yielding stop, a rod and yielding means for normally causing said rod to contact with said stop, of a toggle operably connected with said rod.

5. The combination with a member to be moved of a toggle for moving said member, a rod arranged to engage the knuckle of said toggle, yielding means for actuating said rod and a stop engaging said rod and normally relieving the parts of said toggle from strain.

6. The combination with a member to be moved of a toggle for moving said member, a rod arranged to engage the knuckle of said toggle, yielding means for actuating said rod, a stop engaging said rod and normally relieving the parts of said toggle from strain, and means for adjusting said stop.

7. The combination with a movable member of means for holding said member normally in a given position while permitting it to yield, said means comprising a toggle, a rod connected with the pivot of said toggle and provided with an extension, said extension moving with the knuckle of the toggle, means for actuating said rod, and a stop arranged to contact with said extension.

8. The combination with a movable member of means for holding said member normally in a given position while permitting it to yield, said means comprising a toggle, a rod connected with the pivot of said toggle and provided with an extension, means for actuating said rod, a stop arranged to contact with said extension, and means for adjusting said stop to vary the normal position of said member.

9. The combination with a movable member, a toggle having connection therewith, a yielding device arranged to act on said toggle and thereby exert pressure upon said member, and means arranged to act through

the knuckle of said toggle in opposition to said yielding device for cushioning the rebound of said toggle and relieving its parts from strain.

5 10. The combination with a movable member, a toggle having connection therewith, a yielding device arranged to act on said toggle and thereby exert pressure upon said member, and yielding means arranged to act 10 through the knuckle of said toggle in oppo-

sition to said yielding device for cushioning the rebound of said toggle and relieving its parts from strain.

In testimony whereof I have signed my name to this specification in the presence of 15 two subscribing witnesses.

HENRY W. WINTER.
